TEA BAG SQUEEZER

Leslie W. Roberts, Tucson, Ariz.

Application February 17, 1954, Serial No. 29,086

Term of patent 14 years

(Cl. D44—29)

Fig. 1

Fig. 2

Fig. 3

Fig. 4

To all whom it may concern:

Be it known that I, Leslie W. Roberts, a citizen of the United States of America, residing at Tucson, in the county of Pima and State of Arizona, have invented a new, original, and ornamental Design for a Tea Bag Squeezer, of which the following is a specification, reference being had to the accompanying drawing, forming a part thereof.

Fig. 1 is a perspective view of a tea bag squeezer showing my new design;

Fig. 2 is a top plan view thereof;

Fig. 3 is a longitudinal sectional view taken on the line 3—3 of Fig. 2; and

Fig. 4 is a transverse sectional view taken on the line 4—4 of Fig. 3.

I claim:

The ornamental design for a tea bag squeezer, substantially as shown.
